UNITED STATES PATENT OFFICE.

ANDREW FORREST AND GEORGE MARSHALL SMITH, OF CHICAGO, ILLINOIS.

METAL-CASTING APPARATUS.

Application filed October 25, 1924, Serial No. 745,804. Renewed April 13, 1927.

Our invention relates to metal casting apparatus and is designed to provide new and improved box-pouring means whereby a plurality of ingots may be cast at the same time from a single ladle. Our invention provides means whereby the pouring-box or runner-box while carried independently of the ladle is suspended from the same crane and is detachably connected with the ladle in such manner that when supported in horizontal position beneath the ladle-nozzle it moves as a unit with the ladle as the latter is moved by the crane along a line of molds, and it is free to be moved bodily away from the ladle when desired. Our invention also embodies other novel features as will hereinafter more fully appear.

In the accompanying drawings, which illustrate a practical embodiment of our invention, Figure 1 is a view in side elevation of the apparatus assembled in position above a set of ingot molds; Fig. 2 is a view in front elevation of the same, the suspension devices of the ladle being omitted for convenience of illustration; Fig. 3 is a top plan view, partly in section on the line 3-3 in Fig. 2, part of the ladle being broken away; Fig. 4 is a top plan view of the pouring-box; Fig. 5 is an end view of the same, and Fig. 6 is a central cross-sectional view of the same being taken on the line 6-6 in Fig. 4 with a stopper-mechanism added.

Referring to the drawings, the reference numeral 1 designates a casting ladle having a bottom pouring nozzle 2, stopper 3 and stopper-control mechanism 4 operated by a handle 5 which projects over the usual pouring-platform (not shown) in position to be manipulated by the operator. The ladle is provided with the usual trunnions 6 for a suitable ladle-hanger 7 by which it is suspended from the main hoist 70 of an overhead traveling crane indicated generally at 170, so that the ladle can be moved along above a series of ingot molds 8.

A pouring-box or runner-box 9, supported beneath the nozzle 2 of the ladle, is of sufficient length to extend above a set or nest of molds 8 arranged in the usual manner, and has a plurality of bottom-pour nozzles or ports 10 corresponding in number and location with the molds of a set. In the form shown the box has three such nozzles suitably spaced apart to discharge in the axial lines of the mold-cavities to pour the streams

at the centers of the molds when the latter are in position in the usual manner as shown, it being understood that the dimensions of the box and the number and arrangement of its nozzles may be varied according to the manner of arranging the molds. The box 9 is substantially rectangular in shape and preferably is wider at its center than at its ends to form a central extension or well in rear of its nozzles, as shown for example in Figs. 3 and 4. This contour of the box is advantageous as it enables the ladle-nozzles 2 to be located nearer the center of the ladle bottom, whereby the molten metal is drawn or discharged therefrom more nearly from the center of its mass, and it also disaligns the ladle-nozzle 2 and central box-nozzle 10 when an uneven number of the latter nozzles is employed;

also, it provides a well of sufficient size to form a bath of metal below the ladle-nozzle to prevent the metal being poured therein from splashing on the sides of the box and spattering out of it. Each nozzle 10 is provided with a stopper 11 carried on the inner end of a rod 12 which is controlled by an actuating-mechanism 13 mounted on the box and operated by a handle 14 which is pivoted as at 15 and projects over the pouring-platform in position to be manipulated by the operator; in practice the stopper is a graphite head, and the stopper-rod is sheathed and the box is lined with refractory material as indicated in Fig. 5. The box is suspended from an auxiliary hoist 180 on the traveling crane independently of the ladle and in such manner as to be bodily movable with relation to the ladle and to be suspended in a substantially horizontal position beneath the ladle-nozzle and to move as a unit with the ladle while the latter is moved by the crane along a line of molds.

In the exemplification of this feature of our invention here shown, the trough is provided with an opposite pair of end-brackets 100 16 which are bolted to a carrier designated generally as 17 which is suspended by a hanger 18 from the auxiliary hoist 180 on the traveling crane from which the ladle is suspended. The carrier 17 is in the form of an inverted U-shaped frame which is longer than the ladle and approximately the same width as the diameter of the ladle, and comprises a top cross-piece 19 and opposite depending parallel side-pieces 20, which latter

110

carry at their lower free ends an opposite pair of parallel rails 21 whose outer ends are secured to the side-pieces 20 by braces 22 and whose intermediate portions carry fixed 5 inwardly projecting brackets 23 to which the box-brackets 16 are bolted.

The pouring-box is suspended independently of the ladle so that its weight is taken off the latter, and if occasion requires it can

- 10 be bodily swung away from the ladle to allow the latter to pour directly into the molds and to enable the box to be used with other ladles. Detachable connections, preferably automatic in their attaching and detaching
- 15 functions as the box is moved to and away from the ladle, are arranged between the box-carrier and ladle in such manner that the box and ladle move in unison on the crane when the ladle is moved along the
- 20 molds and the box is free to be bodily moved from position under the ladle-nozzle by merely swinging the box-carrier away from the ladle. In the exemplification shown, the box-carrier is provided near its lower end
- 25 with a cross-band 24 which preferably is shaped to conform to the contour of the ladle, as shown for example in Fig. 3, and preferably carries a spaced set of buffer-springs 25 which take under correspondingly spaced brackets 26 fixed on the front of the ladle, to form a spring-cushion between the box and ladle. Each side-piece 20 of the carrier is provided with a lateral guard 27 which projects rearwardly and inwardly to
- 30 abut against the corresponding side of the ladle and take under a stop-piece 28 fixed on the side of the ladle when the parts are assembled in operative relation. By this arrangement the band 24 and brackets 26 co-
- 35 operate to position the box-well in line with the ladle-nozzle and space the box beneath the same, and the guards 27 and stops 28 cooperate to limit the vertical position of the box with relation to this nozzle; the inter-
- 40 connections thus formed are automatic in the operations of attaching and detaching the box and ladle, and are so arranged that while the ladle does not carry any of the weight of the box these parts are interlocked
- 45 and move as a unit on the crane as the ladle is moved above the molds. Furthermore, the box is adjustable with relation to the ladle to accommodate molds of varying heights by merely operating its hoist, and in all its
- 50 operative positions its rear well allows a central run or flow of metal from the ladle. The spring-buffer cushions the assembly of the box and ladle without any stress or shock, and compensates any pull or tight-
- 55 ness of the cables to prevent tipping the ladle and any movement of the ladle by the action of its cables as it empties. The bottom of the box is shaped so that all the metal runs out without requiring the box to be
- 60 tilted, and the regulation of the pouring by
- 65

the box-stoppers instead of by tipping the box is advantageous as one or more of the box-nozzles can be closed if there is not enough metal in the ladle near the end of its discharge to fill all the molds of a set 70 and thus fill at least one mold and pour one whole ingot at the end of the run, thus preventing any waste or reheating of the metal.

We claim:

1. In a metal casting apparatus, the combination with a traveling crane, and a ladle suspended from the crane and having a bottom pouring nozzle, of a pouring device comprising a carrier suspended from the crane independently of said ladle, a pouring-box on the carrier beneath said ladle-nozzle and having a plurality of pouring passages to supply different molds and a central well in rear of its passages, and independently operated stoppers for said box-passages. 75 80 85

2. In a metal casting apparatus, the combination with a traveling crane, and a ladle suspended from the crane and having a bottom pouring nozzle, of a pouring device comprising a carrier suspended from the crane independently of the ladle, a pouring-box on the carrier beneath the ladle-nozzle and having a plurality of pouring passages, and detachable co-operating means on the carrier and ladle to connect the same for unitary 90 95 movement.

3. In a metal casting apparatus, the combination with a traveling crane, and a ladle suspended from the crane and having a bottom pouring nozzle, of a pouring device comprising a carrier suspended from the crane independently of the ladle, a pouring-box on the carrier, a cross-band on the carrier to position the box in the line of the ladle nozzle, and co-operating means on the 100 105 carrier and ladle to connect the same for unitary movement.

4. In a metal casting apparatus, the combination with a ladle having a bottom pouring nozzle, of a pouring device comprising a carrier suspended independently of the ladle, a pouring-box on the carrier beneath the ladle-nozzle and having a plurality of pouring passages, and co-operating means including a spring-buffer between the carrier and ladle to connect the same for unitary movement. 110 115

5. In a metal casting apparatus, the combination with a ladle having a bottom pouring nozzle, of an inverted U-shaped carrier-frame suspended independently of the ladle, a pouring-box on the carrier having a plurality of pouring passages in its bottom and a central well in the rear of said passages, a cross-band on the lower portion of the carrier, brackets on the ladle, springs between the brackets and cross-band, inwardly directed guards on the sides of the carrier, and stops on the ladle above the guards. 120 125

6. In a metal casting apparatus, a travel- 130

ing crane; a ladle suspended from the crane and having a bottom pouring nozzle, a pouring-box having a plurality of pouring passages, and a box-carrier suspended from the 5 crane independently of the ladle and having means so engage the ladle and brackets to support the box in position below the ladle- nozzle while the ladle is moved along a series of molds.

In testimony whereof we affix our signatures hereto.

ANDREW FORREST.
GEORGE MARSHALL SMITH.
